Delaware

Filed Aug. 20, 1965, Ser. No. 86,656

Term of patent 14 years

(Cl. D57—1)

FIG. 1 is a perspective view looking from the front of a combination visor and headband showing my new design;

FIG. 2 is a side view;

FIG. 3 is a front view; and

FIG. 4 is a top view.

The dominant features of my design reside in the portions shown in full lines, being characterized by the stippled areas to denote contrast encompassed therein.

I claim:

The ornamental design for a combination visor and headband, as shown and described.
